UNITED STATES PATENT OFFICE.

AMANDUS M. HEMBERG, OF MINNEAPOLIS, MINNESOTA.

CAR-DOOR.

1,256,797.

Specification of Letters Patent. Patented Feb. 19, 1918.

Application filed April 17, 1915. Serial No. 22,036.

To all whom it may concern:

Be it known that I, AMANDUS M. HEMBERG, a citizen of the United States, residing at Minneapolis, in the county of Hennepin 5 and State of Minnesota, have invented certain new and useful Improvements in Car-Doors; and I do hereby declare the following to be a full, clear, and exact description of the invention, such as will enable others 10 skilled in the art to which it appertains to make and use the same.

My invention has for its object to provide an improved car door which will take the place, not only of a grain door, but also of 15 an ordinary outside slide door of a box car.

To the above ends, generally stated, the invention consists of the novel devices and combinations of devices hereinafter described and defined in the claim.

20 The invention is illustrated in the accompanying drawings wherein like characters indicate like parts throughout the several views. Referring to the drawings:

Figure 1 is a view in side elevation showing the central portion of a box car and illustrating one of my improved car doors applied thereto;

Fig. 2 is a vertical section taken on the line $x^2 x^2$ on Fig. 1; and

30 Fig. 3 is a horizontal section taken on the line $x^3 x^3$ on Fig. 1.

The numeral 1 indicates the body of an ordinary box car, the same having the usual door opening 2, and the customary horizontally extended door supporting track rail 3 secured on the outer side of the car below the eaves and above the door opening and extending to a point considerably at one side of the door opening.

40 So far as the broad idea of my invention is concerned, the door may be constructed in different ways, but, as shown, it comprises a main door 4 and a supplemental door 5. This main door 4 is preferably constructed from a flat sheet metal or steel plate, which, in width, is considerably wider than the door opening 2, so that it overlaps the door opening, as best shown by full lines in Fig. 3 when the said door is in position 45 to close the door opening. The door 4, when in working position, rests on the floor of the car. The supplemental door 5 is shown as hinged at 6 to the top of the door frame so that it may be swung inward and upward 50 as indicated by dotted lines in Fig. 2, and there held by any suitable means such, for

example, as by a hook hinged to the car roof. The main door 4 and supplemental door 5 have angle iron strips 7 and 8, respectively, attached to their abutting edges, 60 and the outstanding angles of these bars have co-incident perforations through which pins 9 may be passed. Car seals, not shown, may be applied, through perforations in the depending ends of the pins 9, when desired. 65

In its lower portion, the main door 4 is provided with a large discharge port that is normally closed by a gate 10 held thereto at its upper edge. As shown, the gate 10, at 70 its lower free edge, has secured thereto, a small reinforced angle bar 11 that, when the said gate is closed, is directly engaged by a lock bar 12 to hold the gate closed. This lock bar 12 is pivoted to the side of the car at one end, as indicated at 13, and, at its 75 other end, it is adapted to be dropped inside of a retaining bracket 14 secured to the same side of the car, but on the opposite side of the door opening. This lock bar 12 is adapted to be turned into an inoperative position, 80

as shown, by dotted lines in Fig. 1. When it is in its operative position shown by full lines in Fig. 1, it prevents the gate 10 from moving outward. If desired, this lock bar 85 may be secured in its operative position by a car seal suitably applied thereto.

As already indicated, the main door 4 is of such width that it cannot be moved outward through the door opening while in a position parallel to the side of the car. It 90 can, however, be moved outward through the said door opening when moved at an angle to the side of the car. It is supported for such movement by a hanger bracket or arm 15 riveted, or otherwise rigidly secured to the upper central portion thereof, and extending upward and terminating in a swivel socket 16 swiveled on the head of the truck bracket or travel 17 that is equipped with a wheel 18 arranged to run on the track 3. 95

When the door is closed against grain pressure from within the car, the grain pressure may be relieved by opening the gate 10. To open the gate 10, of course, it is first necessary to raise the lock bar 12. When 100 the grain runs from the car sufficiently to afford clearance for a slight inward movement of the door 4, the said door is turned into an oblique position, substantially as indicated by dotted lines in Fig. 3, and then 110 may be swung outward through the door opening. The swivel joint connection be-

tween the hanger bracket 15 and truck bracket 17, of course, permits such movements of the door. When the door is swung outside of the door opening, it may be moved 5 along the track 3 until it is carried along the outer side of the car body to a position entirely at one side of the door opening. The door will be held by gravity close against the side of the car.

10 The door 4 is preferably made of a comparatively thin sheet of steel and is braced and made strong against lateral pressure, by oblique truss bars 19, preferably formed from rolled T-iron or steel. The numeral 15 20 indicates a hand piece applied to the outer face of the door 4.

The door above described, while of comparatively small cost, is highly efficient for the purposes had in view, will serve as an 20 efficient grain door, as well as a door for other purposes. Furthermore, this improved door may be very easily applied to cars already in use. For this purpose, it will not be necessary to close the upper or 25 supplemental door 5. In any event, it may be left open until it is desired to seal the car. In loading the car with grain, the main door will first be closed and then the

car may be properly loaded with grain through the opening afforded above the main door, and this door may be closed only after the grain has been loaded into the car.

What I claim is:

The combination with a car body having a door opening, of a car door having a rigidly and permanently connected body portion that is wider than said door opening and is seated at its side edges against the inner face of the door frame with freedom for inward lateral swinging movement, a track extended above said door opening along the outer side of the car body, a traveler movable on said track, and a flexible hanger suspending said door from said traveler with freedom for lateral and angular swinging movement in respect to said car body, so that the said door may be moved through said door opening when turned at an angle thereto.

In testimony whereof I affix my signature 50 in presence of two witnesses:

AMANDUS M. HEMBERG.
